United States Patent Office

Des. 210,848
Patented Apr. 23, 1968

210,848

DISPENSER
Harvey V. Robb, 33750 Newport Drive,

Warren, Mich. 48092
Filed July 11, 1967, Ser. No. 7,755

Term of patent 14 years

(Cl. D52—2)

FIGURE 3 is a perspective view of the dispenser incorporating my new design and showing, for illustrative purposes only, a container in phantom from which materials may be dispensed.

I claim:

The ornamental design for a dispenser, substantially as shown and described.
